UNITED STATES PATENT OFFICE.

CHARLES T. BROETLER, OF CHICAGO, ILLINOIS.

GLOVE.

Application filed July 14, 1924. Serial No. 725,867.

To all whom it may concern:

Be it known that I, CHARLES T. BROETLER, a citizen of the United States, and a resident of Chicago, in the county of Cook and State of Illinois, have invented certain new and useful Improvements in Gloves, of which the following is a full, clear, and exact description, such as will enable others skilled in the art to make and use the same.

10 My present invention relates generally to gloves having separate patterns for the wrist or the gauntlet portions. One of the principal objects of my invention is to provide a glove which, when finished, will have 15 no seams upon its side edges and which will have the edges of the pattern joined together at the back of the structure so as to present a smooth palm and side portions. It is also an object of my invention to provide 20 a novel manner of joining the edges of the pattern together so as to present an artistic and attractive appearance. A further object resides in providing a glove of the gauntlet type that may be fabricated 25 from two pieces of material and so joined that a neat fit of the glove is obtained. In carrying out my invention I provide a glove that is formed with a single seam, which 30 seam is not in the form of a straight line but of a zig-zag or wavy undulating line, and the line or row of stitching which joins the adjacent edges of the pattern may 35 be continued in a reversed direction to provide an ornamental design upon the back of the glove. The gauntlet or wrist portion is attached to the body of the glove in a novel manner by a single seam and without 40 seams upon its side edges.

I prefer to accomplish the before-mentioned objects and to carry out my invention in substantially the manner hereinafter 45 fully described and as more particularly pointed out in the claims, reference being made to the accompanying drawings that form a part of this specification, in which:

Figure 1 is a plan of the pattern or blank of the main or hand portion of the glove.

Figure 2 is a plan of the gauntlet or 50 wrist portion of the glove.

Figure 3 is a plan of the assembled glove looking at the same from the back.

Fig. 4 is a plan of the assembled glove 55 looking at the palm side of the same with the thumb detached.

In the drawings, I have shown a typical

or preferred embodiment of my invention, and throughout the figures I have employed the same reference characters to designate similar parts wherever the same occur. 60

Referring to the drawings, 5 designates the body or hand pattern, and 6 the gauntlet or wrist pattern. The hand pattern, as seen in Figure 1, is of substantially rectangular shape and provided with a plurality 65 of longitudinally extending slits 7, preferably three in number, in the central portion and extending inwardly from the upper edge of the pattern as laid out in Figure 1. The short slit 8 extends inwardly from the 70 opposite edge of the pattern, preferably in alignment with the central slit above referred to. Equidistant from the center slits, and a corresponding distance from the end edges of the pattern, I fold the blank 75 along the broken lines 9—9 so that the folds and the central seams divide the pattern into four equal parts—in other words the portions outside the folds are approximately one-fourth the width of the pattern. 80 The portions intermediate the folds 9 and the adjacent outside edges of the pattern are provided with slits 10, parallel with the slits 7 heretofore mentioned, and which terminate in substantially the same plane. 85 The edges of the pattern are substantially parallel with each other and with the slits 7 and 10, and are straight edges throughout the length of said slits, which is approximately one-half the length of the hand 90 pattern. Below these straight portions the edges are cut in wavy or undulating lines 11 and 12, the said lines being counterparts, so as to interfit with each other when the pattern has been folded along the broken 95 lines 9 for assembly, as before indicated. In other words, the undulating line 11 at the right of Fig. 1 cuts first into the pattern and then extends outwardly beyond the plane of the adjacent straight portion and then curves around and back into the pattern again, and so on to the lower edge; the waves decreasing in depth towards the wrist edge; and the undulating line 12 at the left of Fig. 1 begins with a curve that 100 extends outwardly beyond the straight edge of the pattern and then curves around and cuts into the pattern in the manner shown. When these curves or undulating edges are brought together, they will fit into each 105 other, and the stitching of a herring bone or chain type can be used to join the same in 110

the manner shown in Figure 3 of the drawings. After the interfitting edges have been joined the stitching is continued in a reversed direction so as to form an ornamental design upon the back of the glove which is in the form of the usual embroidery placed upon gloves of this character.

The lower edge of the pattern 5 is cut 10 with oppositely extending compound or irregular curves 13 and 14 which meet at the central slit 8 so as to provide an inwardly tapered recess 15, the apex of which is at the outer end of slit 8. A suitable 15 thumb opening 16 is formed in the adjacent portion of the body pattern 5 between the short slit 8 and either the right or left fold 9.

The portion of the pattern for forming 20 the gauntlet or wrist 6 is preferably of the same width as the main or hand portion 5 and is illustrated in detail in Figure 2 of the drawings, and the same is preferably folded intermediate its sides along the 25 broken lines 18, corresponding with the lines 9 in the main portion of the pattern. As seen in Figure 2, the edge of the gauntlet pattern 6 which joins the main or body portion has its adjacent edge cut in a curve 30 the reverse of the curvature of the adjacent edges of the body pattern and to clearly illustrate this the gauntlet pattern has been offset so as to bring the interfitting left portion of the gauntlet into alignment with 35 the right portion of the hand of the glove. The curves of this edge of the gauntlet pattern meet centrally thereof in an apex 19 that extends up into the back of the glove and meets the undulating curve of the edge 40 of the hand pattern, while at the end edges the curve extends upwardly again to provide the spaced apices 17, 17, that enter and fit the inwardly tapered recess 15 of 45 the hand pattern. The opposite edge of the gauntlet pattern may be formed in any artistic manner by scalloping or hemming in the customary manner. The chain or herring bone embroidery which is employed 50 on the back of the glove to join the side edges of the hand pattern may be continued along the seam which joins the gauntlet to said hand portion. In the fabrication of the glove made from the patterns herein disclosed it will be noted that no seams will 55 occur along the outer edges of the finished glove and the back of the glove, which has upon it the embroidered undulating seam,

will be artistic and attractive to the eye. It will also be noted that the short slit 8 in the body pattern will register with the 60 edges 20 and 21 of the gauntlet pattern when the structure is assembled so that the latter edges form a continuation of the slit into the gauntlet or wrist portion, as seen in Fig. 4 of the drawings, and any manner 65 of detachably securing these edges may be utilized, such as the stud and socket fastener or button and button hole, or any other well known and desirable device.

While I have herein illustrated and described the specific manner of carrying out my invention, it will be obvious to others that divers modifications thereof may be made without materially departing from the principles I have herein disclosed, and 70 I therefore desire it understood that all such changes or modifications are fully contemplated as coming within the scope of my invention as expressed in the appended 75 claims.

What I claim is:

1. A glove pattern comprising a blank which is slotted along one edge to provide fingers, the edges of said blank transverse to the slotted edge being provided with undulating curves of gradually decreasing depth, the curves upon the transverse edges being reversed with respect to each other whereby the curves interfit when said pattern is folded upon itself parallel with the 80 slits and with the undulating curves at the back of the glove.

2. A glove pattern comprising a blank provided with finger slits extending inwardly from one edge, and portions of the edges of the blank transverse to the slotted edge being formed with counterpart undulated curves that gradually decrease in depth.

3. A glove comprising a blank having its 100 side edges cut on undulating curves to produce interfitting projections, a sinuous line of stitching connecting the side edges of the glove blank and following the undulating curves and forming a seam extending in smooth waves on opposite sides of a medial line and a second line of stitching formed on a curved line with waves alternating 105 with those of the seam and extending in opposite directions to form a symmetrical 110 design.

Signed at Chicago, county of Cook and State of Illinois, this 10th day of June 1924.

CHARLES T. BROETLER.
